[57] CLAIM

The ornamental design for a muscle stimulator, as shown and described.

DESCRIPTION

FIG. 1 is a perspective view of a muscle stimulator showing my new design;

FIG. 2 is a right side elevational view thereof, the left side elevational view being identical;

FIG. 3 is a top view thereof, the bottom view, the front elevational view, and the rear elevational view being identical;

FIG. 4 is a perspective view of a second embodiment thereof;

FIG. 5 is a right side elevational view of the second embodiment, the left side elevational view being identical; and,

FIG. 6 is a top view of the second embodiment, the bottom view, the front elevational view, and the rear elevational view being identical.

Fig. 5
